UNITED STATES PATENT OFFICE.

ABRAHAM M. SMOLENS, OF BROOKLYN, NEW YORK.

FIGURE TOY.

Application filed July 29, 1925. Serial No. 46,691.

This invention relates to figure toys and in particular to one adapted to be held in the hand and spun around by the operation of a cord.

5 A particular object of the invention is to provide a novel toy for the amusement of children which can be operated by drawing on a string, the continued operation of the string speeding up the revolutionary movement of the figure and the rewind of the string providing for the continued operation of the toy without stopping to wind the string about the operating shaft.

10 15 A further object is to provide a toy in which a figure simulating a spinning clown is mounted so that it can be operated by centrifugal force to cause a raising of the arms and legs which are pivoted.

20 A still further object of the invention is to provide in a centrifugally operated toy of this character, a counterweight which will cause rewinding of the operating string for continued operation of the device.

25 Referring to the drawing wherein I have shown a preferred embodiment of my invention,

Figure 1 is a front view of the toy in elevation, the operating position of the figure being shown in outline.

30 Figure 2 is a side view of the toy in section showing the construction of same.

Figure 3 is a section taken on the line 3—3 of Figure 1.

35 Referring to the drawing in detail 5 indicates generally my improved toy which consists of a solid wood counterweight 6 in which is fixed securely the lower end 7 of a vertically disposed operating rod 8, the same carrying loosely at its mid-portion a tubular housing 9 having a side opening 10 therein, through which is adapted to pass the cord or string 11, one end of which is attached to the rod or shaft 8 and adapted to be wound therearound while the end outside 40 the housing 9 is secured to a ring 12 which is of greater diameter than the opening 10 so that it prevents the string from winding completely about the rod 8.

45 The housing 9 acts as a handle and is to be gripped by the fingers of one hand while the other hand draws quickly out on the ring 12 to cause a revolving movement of the rod through the medium of the cord 11 which is wound about the rod. When the rod is thus twirled, and the string completely unwound the counterweight 6 con-

tinues, by its momentum the revolving movement of the rod to thus cause the cord to rewind on the rod, and to again be pulled to operate the toy, this cycle of operation 60 continuing as long as the string is drawn upon.

The housing 9 is held midway of the rod 8 by a collar 13 fixed to the rod 8 in any suitable manner which is disposed beneath the flange 14 of the housing 9; and a ball collar 15 disposed above the housing 9 and also fixed to the rod 8. Thus the rod 8 has a free revolving movement in the housing 9.

The upper end of the rod 8 is split to receive the body 16 of a clown like figure, to which is pivoted the arms 17 and legs 18 all of which normally hang down. The body 16 of the clown has thereon a head and the whole figure is painted to simulate a clown 75 or other amusing toy character.

80 It is evident that a whirling movement of the rod 8 will cause a whirling of the toy figure and centrifugal force will cause the arms and legs to assume a horizontal position to thereby amuse the child operating the same.

85 The counterweight allows the toy to be operated continuously first in one direction and then in the other, by an intermittent pull on the cord.

90 It is evident therefore that I have provided an improved toy for the amusement of children and one which will be harmless and can be operated by a small child. Also a toy which can be manufactured at small cost, is simple of construction and will not get out of order.

Having described my invention what I claim is:

95 A toy comprising a revolvable rod member, a figure at one end of said rod member, a weight at the other end thereof, a housing disposed on said rod and adapted to serve as a finger hold, said housing having an opening therein, a cord passing through said opening and having an end wound about said rod, whereby when the cord is drawn upon, the rod is revolved and the figure operated, a spherical spacing collar fixed to the rod above said housing, and a collar fixed to the rod on the underside of the housing to locate same and maintain it in proper position on the rod.

100 105 110 In testimony whereof I hereunto affix my signature.

ABRAHAM M. SMOLENS.
